UNITED STATES PATENT OFFICE.

BENJAMIN F. MAYO, OF SALEM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST-PULLING MACHINE.

1,288,436.

Specification of Letters Patent. Patented Dec. 17, 1918.

Application filed November 2, 1914. Serial No. 869,824.

To all whom it may concern:

Be it known that I, BENJAMIN F. MAYO, a citizen of the United States, residing at Salem, in the county of Essex and State of Massachusetts, have invented certain Improvements in Last-Pulling Machines, of which the following description, in connection with the accompanying drawings, is a specification, like reference characters on 10 the drawings indicating like parts in the several figures.

This invention relates to machines for separating shoes and lasts to perform the factory operation commonly termed in the 15 trade "last pulling".

In the manufacture of boots and shoes, after the shoes have been lasted and, in the manufacture of welt shoes, after the outsoles and heels have been attached and the shoes 20 have been substantially finished, it is necessary to separate the shoes from the lasts over which the shoes have been shaped. It is the practice to perform this operation by hand by removing the instep blocks, if any, 25 spindling the lasts on stationary last pins, and then manually pulling the shoes from the lasts. Such hand last pulling is hard on the workmen since, in addition to requiring skill, it often and usually requires great 30 strength. Also it is relatively slow. Furthermore, hand last pulling very frequently results in damaging shoes, for example, by tearing the vamps, often at the throats of the vamps, or by bending the shoe soles in 35 the shanks and thus distorting the uppers and often cracking the sole finish. Indeed, it is practically impossible to pull by hand lasts of certain styles or to pull by hand ordinary lasts from shoes of cheap, weak stock 40 without seriously or hopelessly damaging the shoes.

The general object of the present invention is to provide a machine for separating shoes and lasts of whatever type by the use 45 of which machine last pulling operations may be performed quickly and satisfactorily. More particularly, it is the object of the invention to provide a last pulling machine by the use of which shoes and lasts 50 may be separated more quickly than before, without the expenditure of the strength and skill required for the hand operation, and without damaging the shoes.

No completely successful last pulling ma-

chine has heretofore been proposed, nor has any last pulling machine been used to any extent commercially so that, in shoe factories prior to the present invention, so far as I am aware, the last pulling operation has been performed practically universally by hand.

Since, as above suggested, it is an important object of the present invention to minimize the strains upon various shoe parts incident to the last pulling in order to avoid 65 damaging shoes and also to facilitate rapidity of operation, a feature of this invention consists in constructing and arranging the operating parts of the machine so that separation of a shoe and last is accomplished by 70 relative movement thereof along lines imposing minimum strain on the shoe parts. To this end, provision is made for self accommodation of the operating parts to different conditions including, for example, 75 different shapes of lasts and shoes and different relative positions of lasts and shoes during last pulling operations.

In accordance with the foregoing, the illustrated machine provides for effecting 80 necessary relative movement of a shoe and last lengthwise thereof rapidly and without injury to the shoe by organization such that throughout each operation of separating a shoe and last, said relative movement is controlled in time and extent by the resistance 85 to separation of the shoe and last. In consequence, during the successive stages of each last pulling operation, the machine effects lengthwise relative movement of the shoe and last as permitted by said shoe and last, instead of the operating parts following predetermined fixed paths of movement, as in such machines heretofore proposed as 90 have had any provision at all for effecting 95 relative lengthwise movement of a shoe and last. Accordingly, a feature of the invention consists in interconnected pulling parts arranged automatically to vary their relative positions and the lines of pull in response 100 to the resistance offered to the separation of the shoe and last during the successive stages of separation.

A further important feature of the present invention results from the fact that the illustrated machine is organized to effect the above-mentioned lengthwise relative movement of a shoe and last by exerting pulling 105

action on the last in a direction having one component of movement lengthwise of the last and shoe while the shoe is held against lengthwise movement in that direction, the 5 lengthwise component of last movement being controlled by the different relative positions of the shoe and last during separation and finally resulting in completely withdrawing the last from the shoe. Prior 10 to the present invention, no last pulling machine designed to separate shoes and lasts by pulling lasts from shoes while the shoes were held for the removal of said lasts was organized to provide for lengthwise movement of the last along lines automatically 15 varied in response to the resistance offered to separation by the shoe and as permitted by the different relative positions of the shoe and last. Consequently, no machine of this 20 type heretofore proposed was capable of completely separating lasts and shoes of varying styles and sizes unless at the expense of hopelessly tearing and damaging shoes to provide egress for their lasts.

25 Also, preferably and as shown, the machine will be constructed and arranged to be substantially automatic in its operation after the work has been introduced into the machine and properly positioned for the 30 operation thereof.

The foregoing and other objects and features of the present invention, including numerous novel details of construction and combinations of parts, appear from the following detailed description read in connection with the accompanying drawings and the novel features of the invention are defined in the appended claims.

It is to be understood, however, that although 40 both in the foregoing statement and in the following description emphasis is placed upon certain particular objects and features of the invention, as well as upon certain details of construction and combinations of parts, the invention is not intended to be limited thereby.

It is also to be understood that, although the invention is herein shown and described for the purpose of illustration as embodied 50 in a last pulling machine organized to separate shoes and lasts by pulling the lasts from their shoes while the shoes are suitably held therefor, the adaptability of many of the features of the invention and elements and 55 combinations of the illustrated machine for use in a last pulling machine organized reversely to remove shoes from lasts while the lasts are held for removal of the shoes therefrom is fully recognized. It is furthermore 60 contemplated that the invention as a whole, or various features thereof, may have many and widely different applications. Accordingly, the scope of the invention is to be determined by the broadest construction of the 65 terms of the claims permitted by the prior

art. Particularly, the expressions "last pulling", "removing lasts from shoes", and kindred expressions employed in the claims and elsewhere herein are limited in scope to machines which perform the last pulling operation by holding a shoe and operating upon the last to remove it from the shoe only when necessarily and plainly so restricted by the immediate context or by the state of the art, such expressions being commonly employed 70 herein broadly and generically because of the common application in the trade of "last pulling" and the like to the separation of shoes and lasts however performed. Such use of these and other similar expressions is 75 purely for the sake of brevity and general convenience and not at all by way of limitation.

Referring to the drawings,

Figure 1 is a side elevation of an illustrative machine embodying the present invention, with portions of the machine frame broken away to show inclosed mechanism;

Fig. 2 is a perspective view to illustrate the work engaging parts of the machine;

Fig. 3 is a top plan view of the machine;

Fig. 4 is a transverse vertical section showing a shoe held in position for a last pulling operation;

Fig. 5 is a longitudinal vertical section 95 through a holder of an auxiliary shoe holding device;

Figs. 6, 7, 8, 9 and 10 show different stages in a last pulling operation;

Fig. 11 is a longitudinal vertical sectional view 100 through portions of the driving mechanism to illustrate the starting and stopping means; and

Figs. 12 and 13 show opposite sides of the cam disk.

The illustrated machine comprises a heavy upright column designed to stand on a floor and having in its upper part a bearing sleeve 1 (Fig. 1) for a power shaft 2. The shaft 2 carries a loose pulley 3 intended to be connected to a source of power and having a clutch surface formed to be engaged by a cone clutch member 4 splined on the shaft 2. When permitted, the clutch member 4 is moved toward the right (Fig. 1) to close the clutch by a compression spring 5 within the hub of the clutch member 4 and held between said clutch member and a portion of the shaft bearing 1. The spring 5 is permitted to operate the clutch member 4 to close the clutch upon movement of a lever 6, journaled adjacent the end of its forked upper arm (Fig. 3) on the clutch member 4 and operated by a toggle 7, 8, (Figs. 1 and 11) to which is pivoted a rod 9 pivotally connected at its lower end to the rear end of a starting treadle 10, depression of which raises the rod 9 and breaks the toggle 7, 8, to move the lever 6 toward the right (Fig. 1) to permit the spring to close the clutch. The 130

treadle 10 is normally maintained elevated at its free end by a spring 12, the rod 9 being thereby normally pulled down thus depressing the pivotal connection of the rod 9 with the toggle 7, 8 as far as permitted by a stop 13. A turn buckle 14 (Fig. 1) provides for adjustment of the rod 9. The clutch is opened by automatic stopping mechanism a description of which is given hereinafter together with the operation in detail of the above mentioned arrangement for starting the machine.

For holding a shoe for a last pulling operation, the machine is provided with shoe holding means comprising, in the illustrated construction, shoe clamping members arranged to be moved from inoperative positions into operative engagement with a shoe. Movement of the shoe clamping members into operative engagement with a shoe is provided for as follows: Fixed on the shaft 2 is a worm 15 (Figs. 1 and 11) meshing with a worm gear 16 through which the worm 15 drives a cam shaft 20 arranged to make half a revolution for each complete cycle of the machine. On the cam shaft 20 is a cam disk 21 (Figs. 1, 11, 12, 13) having in its periphery two opposed relatively short low parts or depressions 22, 22 (Fig. 12), the remainder of its periphery being uniform in diameter and concentric with its axis. The cam disk 21 operates a lever 25 fulcrumed at 24 (Fig. 1) and carrying on its lower arm a roll A which engages the periphery of the cam disk 21. The upper end of the lever 25 engages and intermittently thrusts toward the left (Fig. 1) and against the pull of return springs 23 a plunger 26 carrying a cross head 27 connected by links 28 to the rear arms of bell cranks 30. The bell cranks 30 are fulcrumed at 29 to fixed portions of the machine frame and their front arms are linked by adjustable bars 32 to frames 35 which carry shoe holding devices for engaging the two sides of a shoe. The frames 35 and the shoe engaging and holding devices carried thereby are alike for the two sides of the shoe.

Each frame 35 has two stems 33, 34 (Fig. 4) movable endwise toward and from a shoe in stationary slideways. At their inner ends the stems 33, 34 carry respectively heel and counter grippers 36, 37. The stems 33, 34 are formed by inner and outer telescoping sections between which are seated relief springs 38, the tension of which can be adjusted by screws 39. Both the heel and counter grippers 36, 37 comprise opposed independent blocks arranged to engage opposite sides of the rear portion of a shoe and having, by reason of their above described mounting and arrangement, substantially right line movement toward and from shoe engaging position upon movement of the frames 35 operated through the above

described connections with the lever 25 and cam disk 21.

The heel and counter gripper blocks may be made of any suitable material. In the illustrated construction, rubber is employed since it combines desirable adhesiveness and resiliency with a non-abrasive quality whereby the said blocks hold a shoe very firmly and at the same time are somewhat self conforming to the contour of the shoe parts 75 engaged without injuring the finish of the shoe. Preferably, the counter gripper blocks are concaved horizontally and lengthwise of a shoe (Fig. 3) to adapt them to the contour of the sides of a shoe counter 80 from the heel breast line rearwardly and the heel gripper blocks are similarly concaved to adapt their work engaging faces to the contour of the sides of a shoe heel from the heel breast rearwardly. The counter gripper 85 blocks also have their work engaging faces concaved vertically and transversely of a shoe to adapt them to the vertical contour of the sides of a shoe counter (Figs. 2 and 4). Similarly, as plainly shown in Fig. 4, 90 the heel gripper blocks have their work engaging faces shaped to conform to the vertical contour of the sides of a shoe heel from the tread face to the heel seat.

In order that the heel and counter gripper blocks may be freely self positioning further to accommodate them to the contour of the sides of a shoe heel and counter from the heel breast line rearwardly, the holders 40, in which the heel and counter gripper blocks 100 are removably carried, are each swiveled on its stem by a vertical pivot 41, a supporting plate 42 (Fig. 4) sustaining the grippers 36, 37 against sagging. The heel and counter grippers 36, 37 are rendered still further 105 self-accommodating to different sizes and shapes of shoes by the above described relief springs 38 which operate to cause the said grippers to engage a shoe with adjustable spring pressure. Also, the before-mentioned 110 adjustable bars 32, connecting the bell cranks 30 to the gripper carrying frames 35, provide for adjusting the extent of shoe engaging movement of the grippers 36, 37 according to varying conditions, particularly 115 for shoes of different widths.

In addition to the described heel and counter clamps 36, 37, the illustrated machine is provided with auxiliary shoe holding means coöperating with the grippers 120 36, 37 to hold a shoe for a last pulling operation by engagement with the shoe sole on opposite sides of the sole. To this end, each gripper carrying frame 35 has a holder 44 (Figs. 3 and 5) into which is threaded an 125 adjustable nut 46 bearing against one end of a spring 47 encircling a stem 48 of a carrier 50 and seated at its other end against an outstanding annular rim on said stem 48. A shoe sole engaging device 45 is dove- 130

tailed into the front end of each carrier 50. The auxiliary holding devices 45 are located relatively to the heel and counter grippers 36, 37 to engage a shoe in the shank and, 5 conveniently, as shown in Fig. 1, well forward in the shank near the line of the break between the forepart and shank. In the illustrated construction, each device 45 comprises a relatively thin flat blade adapt- 10 ed to engage a shoe in the welt crease. The auxiliary shoe holding devices 45 not only coöperate with the shoe holding grippers 36, 37 in positioning a shoe and holding it positioned for a last pulling operation, but 15 at the same time, afford additional support for the shoe, particularly in the region of the shank, to prevent bending the shoe sole and thus cracking or injuring the sole finish.

As in the case of the heel and counter 20 grippers 36, 37, the auxiliary shoe holding devices 45 are constructed and arranged to meet the various requirements of shoes of many sizes and shapes. Preferably, as shown in Fig. 1, the devices 45 are normally 25 inclined at an oblique angle to the vertical to adapt their crease engaging blades approximately to the spring of a shoe shank. To enable the devices 45 to be movable from said position according to the spring of a 30 particular shoe shank, each carrier 50 for a shoe sole engaging device 45 has a vertical slot entered by a roll 49 on a stationary guide 51 held by a bolt 53 (see particularly Fig. 5) passing through a slot 55 35 in the frame 35, the slot 55 as shown in Figs. 2 and 3, being long enough to allow tipping or swinging adjusting movement of the carrier 50 about its lengthwise axis. At the same time, the described construction pro- 40 vides for holding each device 45 against turning as it slides toward and from the work. Further adjustment of each device 45 is provided for by a screw 52 (Fig. 5) and lock nut by means of which said devices 45 45 may be adjusted up or down in a generally vertical direction and secured in adjusted positions to adjust them for shoe shanks differing in height. Also, as in the case of the heel and counter grippers 36, 37, the 50 auxiliary shoe holding devices 45 are pressed against the work under adjustable spring pressure by means of the springs 47 and adjusting nuts 46 before mentioned.

In the use of the machine, the described 55 power driven mechanism provides for automatically and substantially simultaneously advancing the shoe holding grippers 36, 37 and the auxiliary shoe sole engaging devices 45 yieldingly into operative engagement 60 with a shoe when the power shaft 2 turns the cam disk 21 in the direction of the arrow from the position shown in Fig. 1. The grippers 36, 37 are thus given a right line forward movement horizontally and substantially at right angles to the longitudu-

dinal median line of a shoe to clamp the rear portion of the shoe, while the auxiliary shoe holding devices 45 are similarly moved to enter the welt crease well forward in the shank and, by engagement with the shoe 70 sole, to sustain the sole against the last pulling movement. The described contour of the cam disk 21 operates to cause the shoe to be held securely clamped until the roll A on the lever 25 drops into one of the depressions 22 in the periphery of the cam disk 21 at the end of a half revolution of the shaft 20, whereupon the springs 23 retract the shoe engaging devices 36, 37 and 45 to the normal inoperative positions shown in 80 Fig. 3, thereby releasing the shoe. During the time the shoe is held thus clamped, the last is pulled from the shoe by last removing means to be described.

If desired, the heel grippers 36 may sometimes be omitted and the shoe counter grippers 37 alone used to clamp the rear portion of the shoe. Also, in some classes of work where comparatively little resistance is offered to the separation of a shoe and its 90 last, particularly in the early stages of the last pulling operation, the shoe sole engaging devices 45 may be omitted, the described clamping means for the rear portion of the shoe alone being relied upon to hold the 95 shoe.

In order that separation of a shoe and last may be effected, it is essential that there be relative movement of the shoe and last lengthwise thereof. In the illustrated machine, such relative movement is provided for by holding the shoe against lengthwise movement in one direction, the last removing means operating to effect lengthwise last movement in said direction while the shoe is 105 so held. With this in view, the concaved shoe holding devices 36, 37 are arranged to embrace the rear portion of a shoe sufficiently to form an abutment for the shoe against lengthwise movement heelward. To 110 the same end and also to facilitate correct positioning of a shoe, the illustrated machine is provided with a shoe back gage 54 (best shown in Fig. 2) preferably covered, for example, by a strip of rubber 56 or other 115 resilient and non-abrasive material. As shown in Fig. 2, the illustrated back gage 54 comprises a plate bent at substantially a right angle to provide a vertically disposed portion which constitutes the shoe engaging part of the back gage, and a horizontally disposed portion adjustably secured to the machine frame by means of a lock nut 57 entering a relatively long slot 59 in said horizontal portion of the back gage 120 plate. The nut and slot construction 57, 59 provides for adjustment of the back gage 54 for shoes of different lengths. In addition to serving as a gage to facilitate initial location of a shoe by engagement with the 125 130

counter at the back of the shoe, the back gage 54 also constitutes an additional abutment for the shoe, coöperating with the shoe grippers 36, 37 to prevent lengthwise movement of the shoe heelward.

The illustrated machine is organized to pull a last from a shoe, while the shoe is held in the manner above described, by exerting upon said last a compound pulling action in directions to effect a complete withdrawal of the last from the shoe. To this end, the machine is provided with a last holder arranged to withdraw a last from a shoe by a generally downward last movement having an increasing component of lengthwise last movement. The illustrated arrangement is such that the last is given an initial movement substantially perpendicularly to the plane of the shoe bottom, the mechanism exerting constantly an increasing lengthwise draft on the last so that, as soon as the heel end of the last has moved downwardly far enough so that it can clear the counter portion of the shoe, the last moves downwardly out of the shoe with an appreciable component of lengthwise movement.

For engaging and holding a last and withdrawing said last from its shoe while the shoe is held by the clamping devices 36, 37, 45, the illustrated machine is provided with a last support and holder comprising a spindle arranged to be tipped to cramp or bind it in holding engagement with a last and operatively connected with the cam shaft 20 to cause the last spindle to be moved in a generally downward direction, the organization being such as to cause the last holding spindle to effect lengthwise last movement as permitted by the shoe and last.

To cause the last holding spindle to be thus operated from the cam shaft 20, the cam disk 21 on said cam shaft 20 carries a double armed cam 58 (see particularly Figs. 12 and 13) having a hub embraced by the forked upper end of a thrust bar 60 (Figs. 1, 12 and 13) arranged, by engagement of a roll 63 on said bar 60 with said cam 58, to force downwardly a plunger supporting lever 61 fulcrumed at 62 and normally upheld by a counter weight 64 (Fig. 1). The lever 61 is operatively connected with the last spindle by a plunger 65 arranged to be reciprocated upon movement of the lever 61. The plunger 65 passes through a vertical guide 66 between and secured to a pair of guide plates 67, 68. To the upper end of the plunger 65 a bar 66 is secured by a pivot 67 extending transversely of the machine and consequently transversely of a shoe and last operatively positioned in the machine. The upper end of the bar 66 is connected, by a similarly arranged pivot 68, to the rear upper end of a frame 70 guided between the plates 67, 68 and constituting a swinging car-

rier for the last spindle. The last spindle comprises a pin 72 carried on the front end of the frame 70 and adapted to enter the usual last pin hole of a last and to bind or cramp against the side wall of the last pin 70 hole in holding engagement with the last by being tipped about the pivotal points 67, 68.

The machine comes to rest with the last holding spindle 72 and its supporting and operating mechanism in the positions shown in Fig. 2, the plunger 65 being fully elevated. A shoe, having therein a last to be pulled, is presented by mounting the last on the spindle 72. The shoe is then elevated by the operator into position to be engaged and held by the shoe clamps 36, 37 and 45, for example, by the operator manually swinging the last spindle carrier 70 upwardly (as indicated in Fig. 1) to move the last spindle 72 and last and shoe thereon to bring the heel end of the shoe into proper position against the back gage 53 and the shoe at the proper position relatively to the devices 36, 37 and 45, as illustrated in Figs. 1 and 4, in which position the shoe bottom is substantially horizontal, with the shoe heel between the heel grippers 36, the shoe counter between the counter grippers 37, and the shoe shank similarly located between the shoe sole engaging auxiliary blades 45.

When the starting treadle 10 is depressed, the shoe engaging and holding devices 36, 37 and 45 are brought as above described, into yielding clamping engagement with the shoe after which, and while the shoe is thus held, the plunger 65 is forced downwardly by the cam 58 through downward movement of the thrust bar 60 and plunger supporting lever 61. As the plunger 65 descends, it operates to pull down the rear end of the last spindle carrier 70 with the result that, during the first part of the descent of the plunger 65, the last spindle 72 is tipped from the position of Fig. 6 into firm holding engagement with the last thereon (Fig. 7) and thereafter until the completion of the last pulling operation maintained tipped in said holding engagement (Figs. 8 and 9).

To facilitate effecting and maintaining initial last holding engagement of the last spindle with the last and to prevent the last spindle from dropping out of the last pin hole after the shoe has been positioned to be engaged and held by the shoe holding means but before downward movement of the plunger 65 operates to effect secure holding engagement of the last spindle with the last, the illustrated machine is provided with a spring plunger 73 carried in the bar 66. This spring plunger 73, by acting against a portion of the carrier frame 70 depending below the pivot point 68, tends to swing the carrier 70 and last spindle 72 automatically at an oblique angle to the

normal direction of the last pin hole and in the direction to tip and maintain the last spindle in clamping engagement with the last.

- 5 Preferably, the last spindle carrier 70 is formed with an abutment 74 which constitutes a stop to limit depression of the carrier 70 by engagement with the bar 66 (see for example, Fig. 2). Also, in the illustrated construction, the bar 66 and the plunger 65 have coöperating stops 75, 76 (Fig. 1) to limit forward and downward tipping of the bar 66 when the parts are idle in shoe receiving position (Fig. 2).
- 15 The operation of the above described last removing means in pulling a last from a shoe will best be understood by reference particularly to Figs. 6 to 10, the arrows indicating the behavior of the parts. The first part of the downward movement of the plunger 65 operates as above stated, to pull down the rear end of the last spindle carrier 70 to the oblique position shown in Fig. 7, in which position the last spindle is securely cramped in holding engagement with the last. Thereafter, during the descent of the plunger 65, the last spindle is operated to pull the last downwardly and lengthwise heelward until the last is completely removed from the shoe. By reason of the pivotal connections 67 and 68, the plunger 65 at all times during its descent exerts upon the last spindle a distinct and increasing pull backwardly. This not only tends to tip the last spindle 72 more and more, thus causing it to hold the last more securely in proportion as the tendency of the last to separate from the last spindle increases, but, during the generally downward last movement, the last spindle is caused to exert upon the last a constant and progressively increasing pull heelward. The result is that, as the last is moved downwardly, it is also moved lengthwise relatively to the shoe as soon and as much as permitted by the relative positions of the last and shoe. During the initial stages of the last pulling movement, from the position of Fig. 7 to approximately the position of Fig. 8, the last is so held by the counter materials that the last movement is substantially perpendicular to the plane of the shoe bottom. As soon, however, as the last has moved relatively to the shoe far enough so that the heel end of the last can clear the counter portion of the shoe, at which time the last is permitted to have a very decided lengthwise movement from the position shown in Fig. 8 to the position in Fig. 9, the lengthwise pull exerted upon the last by the last pulling mechanism operates automatically to withdraw the last lengthwise heelward from the shoe (Fig. 10).

An important feature of the present invention consists in the fact that, by reason

of the pivotal connections 67, 68, the last spindle 72, instead of following a definite path or paths of movement irrespective of differences in resistance to separation offered by a given shoe and last at different stages in the last pulling operation, is "floating" and is freely self-positioning to accommodate itself always and automatically to different conditions and changing relative positions of shoe and last to cause each last pulling movement to be effected at all times along the line offering minimum resistance to separation. This facilitates rapid operation and avoids injuring the shoe. Thus, for example, the machine does not overstrain the vamp and back of a shoe as would be likely to be the case if, before the heel end of the last cleared the counter, an excessive lengthwise pull were exerted on the last. On the other hand, as soon as permissible, the machine automatically effects a decided lengthwise last movement to withdraw the last heelward from the shoe.

The automatic accommodation of the line of pulling force to lines of pull offering less resistance to separation is effected through the freedom of the pivotally inter-connected pulling members 70, 66, and 65, to swing relatively to each other to change the line of pulling force to lines offering less resistance to separation during the successive stages of separation of each specific shoe and last operated upon.

To illustrate, and referring particularly to Figs. 7-9 of the drawings: the first slight movement of the jack 70 to the right when the plunger 65 begins to descend cramps the pin 72 in the last thimble or hole and locks the last to the jack. Further movement of the plunger tends to swing the jack with its last still further to the right but this movement would be in the direction of greatest resistance because of the interposed shoe counter. The resistance offered by the counter to such movement, acting through jack 70, swings the latter on its pivot 68 during the continued descent of the plunger so that the line of pull on the last is downwardly along a line offering less resistance as suggested in Fig. 8. The interconnected pulling members 66, 70, form a bent toggle which tends to straighten out, as permitted by the different relative positions of the shoe and last and the resistance offered to separation, as the plunger 65 continues to descend, this straightening out tendency and the movement of the plunger in a vertical plane rearwardly of the shoe, producing the lengthwise heelward component of movement of the last and its carrier.

Continued descent of the plunger from the position of the parts shown in Fig. 8, therefore, tends to pull the last diagonally downwardly and rearwardly as permitted by the successive relative positions of the

last and shoe and the resistance offered to separation. This resistance to separation acting against the jack 70 will swing the jack still further on its pivot 68 and will 5 swing the connected bar 66 on its pivot 67 until the pull on the last is in a direction offering less resistance—in the illustrated case, in a direction to pull the last diagonally downwardly and rearwardly with its wide 10 ball portion drawn outwardly through the yielding unfastened edges of the quarters, as will be seen from Figs. 8 and 9.

The action will differ somewhat with differences in the size and style of the specific 15 shoes and lasts operated upon. The interconnected pulling members, through their freedom to swing into different relative positions and lines of pull responsively to the resistance offered to separation, will be positioned automatically as described, according 20 to the lines of pull offering less resistance to separation in each particular case, so that the machine is adapted to all shoes and lasts without adjustment for different lines 25 of pull in specific cases. In all cases the lengthwise heelward component of movement (which changes the substantially downward pull to a diagonally downward and rearward movement) increases substantially 30 after the last heel has cleared the edge of the shoe counter but only as permitted by the relative positions of the shoe and last and the consequent resistance to separation.

By reason of the relatively greater resistance offered to separation of a shoe and last during the early stages of the last pulling movement, it has been found in practice that the last pulling operation can not properly proceed as fast during the early part thereof 40 as is permissible, for example, after the heel end of the last has been moved relatively to the shoe far enough so that it can clear the shoe counter, after which there is less resistance to the last pulling movement so that 45 the remainder of the operative movement of the last spindle can be effected relatively rapidly without danger of injury to the shoe. To provide for movement of the last removing means slowly enough during the 50 early stages of the last pulling operation to avoid damaging the shoe and at the same time to provide for greater speed when permissible in order to perform last pulling operations with desirable rapidity, in the illustrated machine, each half of the cam 58, 55 which operates the last spindle 72 through the plunger 65, the plunger supporting lever 61, and thrust bar 60, is formed to initiate the last pulling movement at a relatively 60 slow speed and to change the speed of the last pulling movement to a decidedly higher speed when the resistance to separation of shoe and last has decreased sufficiently to permit.

65 To this end, and also in order that the

shoe clamps 36, 37, 45 may be brought into shoe holding engagement with a shoe before the last pulling movement is initiated, the double armed cam 58 is arranged, as plainly shown in Figs. 12 and 13, so that, when the 70 machine is started with the parts in the positions shown for example, in Fig. 12, upon rotation of the cam 58 in the direction of the arrow, the cam 58 does not begin to move the thrust bar 60 through the roll 63 until 75 the operating half of the cam 58 has moved from the position shown in Fig. 12 to approximately the position where the point marked α engages the said roll, at which time the last pulling movement is initiated 80 at a relatively slow speed. When approximately the point γ engages the roll 63, by reason of an abrupt change in the contour of the cam 58, a considerably higher speed is automatically imparted to the last spindle 85 72 through the plunger 65 and intermediate connections.

It should also be noticed that the above described worm and worm gear 15, 16 constitute a speed reducing element whereby 90 the speed of the operating parts of the machine is made less than the speed of the shaft 2 for the reason that it has been found desirable to run the machine at a less speed than the speed at which power driven shafts 95 in factories are ordinarily run.

As the plunger 65 completes its descent, the last is completely pulled out of the shoe and the frame 70 drops to a forwardly tipped position (Fig. 10), convenient for 100 removal of the last from its spindle 72, in which position the forward tipping movement of the frame 70 is arrested by the stops 75, 76. The plunger 65 is then raised before the end of the cycle of the machine to the 105 position shown in Fig. 2 so that it will be ready for the convenient application of another shoe to the spindle and the manually effected lifting of the shoe into position to be engaged by the shoe clamps 36, 37, 45. 110 During the last part of the cycle of the machine and after the completion of the last pulling movement, the shoe clamps release the shoe from which a last has been pulled and come to rest in the normally inoperative position of Fig. 3 ready for the reception of the next shoe. In practice, the operator catches the released shoe in one hand, while removing from the last spindle with the other hand the last just pulled, and then 115 picks up another shoe, spindles it, and tips it upwardly into position to be clamped,— all in one series of continuous movements followed by the treadling of the machine to cause it successively to clamp the shoe and 120 withdraw the last therefrom.

For automatically stopping the machine at the end of its cycle, there is provided in the illustrated machine mechanism before mentioned, which mechanism is described 130

but not claimed herein, this mechanism forming the subject-matter of United States Letters Patent No. 1,196,836, granted Sept. 5, 1916, on application of John M. Benjamin.

Referring to Figs. 1, 3, and 11, and particularly to Fig. 11, the lever 6 is trunnioned at 71 on a hub 83 on the male clutch member 4. The upper end of the lever 6 is pivoted at 77 to the rear end of a link 78 guided between fixed ears 79 upstanding from the bearing 1 in which the shaft 2 turns. The front end of the link 78 is forked (Fig. 11) to embrace the hub of the cam disk 21 in such manner as to allow sliding movement of the link 78 forwardly and backwardly parallel to the shaft 2. On one of its side faces, the link 78 has a projection 80, best shown in Fig. 11, the outer edge face of which projection is eccentric to the axis of the cam shaft 20 and normally located to be engaged by one or the other of rolls 81, 82 carried on one side of the cam disk 21, such engagement forcing the link 78 forwardly toward the left (Fig. 11) and thereby moving the lever 6 in the direction to pull the clutch member 4 out of driving contact with the coöperating clutch face on the continuously running pulley 3 and locking the said clutch member in inoperative position.

The stopping mechanism just described coöperates with the treadle 10 and associated parts heretofore described as follows: When the parts are in their normal positions, as before stated, the spring 12 operates through the treadle 10 and rod 9 to hold the toggle 7, 8 in the position shown in Fig. 11, that is, approximately straight with the link 7 in engagement with the stop pin 13. Upon depression of the treadle 10, the rod 9 is raised to break the toggle 7, 8, as indicated in broken lines in Fig. 11. This toggle movement results in movement of the lower end of lever 6 toward the right (Fig. 11) since the outer end of link 8 turns about a fixed pivot. Because of the fact that, in the normal positions of the parts, the cam disk 21 is at rest with either the roll 81 or the roll 82 in engagement with the projecting portion 80 of link 78 and the link 78 thereby held stationary at the left hand limit of its movement (looking at Fig. 11), upon depression of the treadle 10 and consequent movement of the lower end of lever 6 toward the right (Fig. 11), said lever 6 fulcrums about its connection 77 with the link 78, thereby allowing the spring 5 to snap the clutch member 4 toward the right into clutching engagement with the driving pulley 3. Thereupon, the shafts 2 and 20 are set in motion and the roll 81 or 82 passes off the projection 80 on the link 78, leaving the link 78 free to slide endwise toward the right (Fig. 11). The operator is expected 65 to remove his foot from the treadle as soon

as the machine is started, whereupon the spring 12 restores the toggle 7, 8 to the position shown in Fig. 1 and in full lines in Fig. 11, thus swinging the lower end of lever 6 toward the left (Figs. 1 and 11). In this movement, the lever 6 shifts its fulcrum and turns about the axis of its trunnion 71, since the spring 5 is pressing the clutch member 4 and consequently its trunnion 71 toward the right. Such movement of the lever 6 toward the left draws the link 78 toward the right and thereby locates the projection 80 in the path of the approaching roll 82. When said roll 82 engages the projection 80, the link 78 is thereby forced toward the left and, inasmuch as the toggle 7, 8 holds the lower end of lever 6 against movement toward the right, movement of the link 78 toward the left causes the lever 6 to fulcrum about its connection 84 with toggle link 7, in consequence of which the clutch member 4 is pulled out of clutching engagement with the pulley 3 and the machine is stopped. In the illustrated construction, this disconnection of the clutch members takes place automatically at the end of a half revolution of the cam shaft 20 which occurs at the end of a complete cycle of the machine. It will be noted that, in the construction described, all of the power driven parts of the machine receive their movements from a single cam disk 21, provided with the peripheral depressions 22 and having the double armed cam 58 on one side and the cam rolls 81, 82 on the other side. This invention, therefore, provides a simple, compact and strong driving mechanism for the machine.

With respect to the foregoing, it is to be understood that, within the invention, various changes may be made in the shoe and last engaging devices and also in the construction and organization of the operating mechanism therefor. In addition to changes and modifications hereinbefore indicated, many other changes in construction and arrangement, such as will readily occur to those skilled in the art, may be made without departing from the spirit and scope of the invention.

Having fully explained my invention and described in what manner the same may be embodied, what I claim as new and desire to secure by Letters Patent of the United States is:—

1. In a last pulling machine, in combination, shoe holding means and last holding means arranged for relative movement to effect the separation of a shoe and its last, and means for effecting said relative movement including interconnected pulling members relatively movable without predetermined paths of movement coöperating with one of said holding means and constructed and arranged automatically to change their 130

relative positions and line of pull during the successive stages of shoe and last separation in response to the resistance offered to separation by the specific shoe and last operated upon.

2. A last pulling machine having, in combination, shoe holding means, last holding means, and mechanism for effecting relative movement of said means to cause separation of the shoe and last, including interconnected pulling parts arranged for relative movement to vary the line of pull and automatically to change their relative positions during the relative movement of said means 10 in response to the resistance offered to separation during the successive stages of separation.
3. In a last pulling machine, in combination, a shoe holder, a last holder, a mounting 20 for one of said holders including interconnected pulling members relatively movable without predetermined paths of movement constructed and arranged automatically to change their relative positions and line of 25 pull during the successive stages of shoe and last separation in response to the resistance offered to separation of the shoe and last, and mechanism for operating said pulling members to separate a shoe and its last.
4. A last pulling machine having, in combination, shoe grippers and a last holding spindle relatively movable to separate a shoe and last, together with a carrier for one of said elements having interconnected 35 pulling parts relatively movable to vary the line of shoe and last separating pull and arranged automatically to vary their relative positions and the line of pull in response to the resistance offered to separation by the 40 last and shoe.

5. In a last pulling machine, means for holding a shoe for the removal of a last therefrom, and last removing means including interconnected pulling parts relatively 45 movable to vary the line of pulling force and organized automatically to vary their relative positions and the line of pull during the successive stages of last and shoe separation in response to the resistance offered 50 to separation by the last and shoe.

6. In a last pulling machine, a shoe holding clamp, a last holding support, operating means for said support including interconnected pulling parts between said last support and its operating means arranged for relative movement to vary the line of pulling force and automatically operative to change their relative positions and line of pulling force during the successive stages of last 55 and shoe separation in response to the maximum resistance offered to the separation of the shoe and last.
7. In a last pulling machine, in combination, shoe holding means, a last holding 60 spindle, a swinging carrier for said spindle

arranged to be manually moved to position a last and the shoe thereon to coöperate with said shoe holding means, means for effecting movement of said last carrier to remove the last from a shoe including an operating member and pivotal connections between said last carrier and said member so arranged that upon movement of said operating member said carrier is automatically positioned to accommodate said spindle and a last thereon to the varying lines of pull required by the different relative positions of a shoe and last during the successive stages of separation.

8. A last pulling machine having, in combination, a last holder and a shoe clamp, with power-operated mechanism arranged to separate a shoe and last by movement of the last in a direction generally perpendicular to the plane of the shoe bottom with an increasing lengthwise component of movement of the last as permitted by different relative positions of the shoe and last.

9. A last pulling machine having, in combination, a last holder, a shoe clamp, and power operated mechanism for relatively moving said holder and said clamp including interconnected pulling members relatively movable without predetermined paths of movement and free to effect lengthwise relative movement of a shoe and last as permitted by different relative positions of said shoe and last.

10. A last pulling machine having, in combination, a last holding spindle, shoe grippers, and mechanism for effecting relative movement of said spindle and said grippers to separate a shoe and last, said mechanism including interconnected relatively movable pulling members having free pivotal connections and without predetermined paths of movement operative to effect lengthwise relative movement of said shoe and last as permitted by different relative positions thereof.

11. A last pulling machine having, in combination, a last holding device, a shoe holding device, an operating member for effecting movement of said last holding device in a direction to separate the last from the shoe, a power driven shaft, and a speed reducing connection between said shaft and said operating member, whereby the speed of said separating movement is reduced below the speed of said shaft.

12. A last pulling machine having, in combination, a last holder, a shoe clamp, a cam for effecting movement of said last holder in a direction to effect separation of the last from the shoe, a power driven shaft, and a speed reducing device operatively connected to said shaft and said cam, whereby said cam operated movement is produced at a less speed than the speed of said shaft.

13. A last pulling machine having, in

combination, shoe holding means, last engaging means arranged for tipping movement relatively to a last supported thereby to exert a binding or cramping action on a 5 last, and mechanism for relatively moving said shoe holding means and said last engaging means in a direction to separate a shoe and last.

14. A last pulling machine having, in 10 combination, means for holding a shoe, a last holder arranged for tipping movement to bind or cramp the last holder in a last in said shoe to oppose separation of the last and holder, and means for relatively moving 15 said shoe holding means and said last holder to separate the shoe and last.

15. A last pulling machine having, in combination, shoe holding means, a last spindle arranged for tipping movement to exert a 20 binding or cramping action on a last in a shoe to oppose separation of the last from the last spindle during the last pulling operation, and mechanism for relatively moving said shoe holding means and said spindle 25 to separate a shoe and last.

16. A last pulling machine having, in combination, shoe holding means, a tipping last holder arranged to offer increasing resistance to separation of a last from said holder 30 in proportion as the tendency of said last to separate from the holder increases, and means for relatively moving said shoe holding means and said last holder to separate a shoe and last.

35 17. A last pulling machine having, in combination, means for holding a shoe, a last spindle, a carrier for the last spindle arranged for tipping movement to cramp the last spindle in the last to oppose separation 40 of the last and last spindle, and means for relatively moving the shoe holding means and the last spindle carrier to separate a shoe and last.

45 18. A last pulling machine having, in combination, a shoe holder, a last spindle, a carrier for the last spindle pivoted for tipping movement to cramp the last spindle in holding engagement with a last, and means for relatively moving said shoe holder and said 50 carrier to separate a last and shoe.

55 19. A last pulling machine having, in combination, a shoe clamp, a last holding spindle, a swinging carrier for the last spindle, and means for effecting relative movement of said clamp and said last spindle to separate a shoe and last, said carrier operating during said relative movement to tip said last spindle to cause it to offer increasing resistance to separation of a last therefrom in proportion as the tendency of said last to separate from said spindle increases.

60 20. A last pulling machine having, in combination, shoe holding means, a last holder, and means for tipping said last holder to cramp it in last holding engagement and

thereafter relatively moving said shoe holding means and said last holder to separate a shoe and last.

21. In a last pulling machine, the combination with a shoe holder and a last spindle, 70 of means for tipping said last spindle to cramp it in last holding engagement and thereafter relatively moving said shoe holder and last spindle to separate a shoe and last.

22. A last pulling machine having, in combination, a shoe clamp, shoe holding means, a last holder mounted to be tipped into holding engagement with a last, and means for operating said last holder to pull said last 75 from its shoe.

80 23. A last pulling machine having, in combination, shoe holding means, a last holder mounted for tipping movement into holding engagement with a last, operating means for said holder, and connections from said operating means to said holder operating to cause said holder to be tipped into holding engagement with a last and thereafter to pull said last from its shoe.

85 24. A last pulling machine, having, in combination, shoe holding means, a last holder, and means for tipping said last holder to cramp it in holding engagement with a last and thereafter operating said last holder to pull a last from its shoe, said last-named means acting upon the last spindle to cause it to offer increasing resistance to separation of the last from the last spindle in proportion as the tendency of the last to separate from the last spindle increases. 100

25. A last pulling machine having, in combination, shoe holding means, a last spindle, an operating member, and connections from the operating member to the spindle acting upon movement of the operating member to cause said spindle to be tipped into binding engagement with a last thereon and thereafter to pull said last from its shoe.

105 26. A last pulling machine having, in combination, a shoe clamp, a last spindle, an operating member, and pivotal connections from said operating member to said last spindle operating to tip said last spindle into holding engagement with a last and thereafter to pull said last from its shoe.

110 27. A last pulling machine having, in combination, shoe holding means, a last spindle, a swinging carrier for said spindle, an operating member, and an intermediate 120 member pivotally connected to said carrier and to said operating member whereby upon movement of said operating member said spindle is moved into holding engagement with a last and thereafter operated to pull 125 said last from its shoe.

28. In a last pulling machine, the combination with shoe holding means, of a last holder, a swinging carrier therefor, yielding means tending to swing said carrier and last 130

- holder in a direction to tip the last holder into cramping engagement with a last thereon, and means for relatively moving said shoe holding means and said last holder to 5 separate a shoe and last. 70
29. A last pulling machine having, in combination, shoe holding means, a tipping last spindle, power driven means operating to tip said last spindle to cramp it in holding engagement with a last and thereafter to move the last spindle to pull the last from its shoe, and auxiliary means acting on said last spindle to tend to tip the last spindle for effecting and maintaining an initial last 10 holding engagement to hold said spindle against accidental separation from said last until said power driven means becomes effective to cramp the last spindle in the last. 15
30. A last pulling machine having, in combination, shoe holding means, a last spindle, a swinging carrier therefor, a spring pressed plunger pressing against said carrier in a direction to tip said last pin into binding engagement with a last, and means 20 for relatively moving said shoe holding means and said last spindle to separate a shoe and last. 25
31. A last pulling machine having, in combination, shoe holding means, last holding means manually movable in a direction to bring a shoe on a last engaging said last holding means into operative relation to said shoe holding means, and means for moving said last holding means in a direction 30 to pull a last from its shoe. 35
32. A last pulling machine having, in combination, shoe holding means, a last spindle arranged for swinging movement to bring a shoe on a last mounted on said spindle into operative relation to said shoe holding means, power driven means for effecting relative movement of said shoe holding means and said spindle to separate a shoe and last, said means operating to maintain 40 last holding engagement between said last spindle and said last, and means operating automatically to establish and maintain preliminary holding engagement between the last spindle and the last to prevent accidental separation of the last from the last holding means before said power driven means becomes effective to maintain said last holding engagement. 45
33. A machine for removing lasts from shoes having, in combination, means for holding a shoe for removal of a last therefrom and power actuated means operating upon said last to remove the last completely from said shoe while the shoe is held by said holding means including means for effecting 50 lengthwise last movement. 55
34. A machine for pulling lasts from shoes having, in combination, a clamp for holding a shoe for removal of a last therefrom and power actuated last pulling means 55
- arranged to exert upon said last a compound pulling action in directions to effect a complete withdrawal of the last from said shoe while the shoe is held by said holding means. 70
35. A machine for pulling lasts from shoes having, in combination, a clamp for holding a shoe for the removal of a last from within the shoe and power actuated last pulling means arranged to exert upon 75 a last a compound pulling action in directions substantially perpendicular to the plane of the shoe bottom and lengthwise of the last and its shoe. 80
36. A last pulling machine having, in combination, means for holding a shoe, last holding means, and power-operated mechanism for effecting relative movement of said means including lengthwise last movement. 85
37. A machine for removing lasts from shoes having, in combination with means for holding a shoe for a last removing operation, power-operated last removing means movable to effect last movement lengthwise of said shoe. 90
38. A last pulling machine having a shoe clamp in combination with a last holder movable to withdraw a last lengthwise heelward from a shoe and power-operated mechanism to move the last holder to withdraw a last. 95
39. A machine for removing lasts from shoes having, in combination, means for holding a shoe for the removal of a last therefrom and power actuated last removing 100 means operating when permitted by the relative positions of the shoe and last to effect lengthwise movement of the last relatively to the shoe. 105
40. In a last pulling machine, in combination, means for holding a shoe for the removal of a last therefrom, and power-operated last removing means arranged to exert an increasing lengthwise pull upon the last. 110
41. In a last pulling machine, in combination, means for holding a shoe, a last holder, and operating means for said holder including pivotal connections operating to cause the last holder to effect an increasing lengthwise last movement. 115
42. A machine for removing lasts from shoes having, in combination with means for holding a shoe for the removal of a last therefrom, power operated mechanism for automatically withdrawing a last from a shoe by movement of the last in a direction generally perpendicular relatively to the plane of the shoe bottom with a substantial component of last movement lengthwise of the shoe and last. 120
43. In a machine for removing lasts from shoes, in combination with means for holding a shoe for the removal of a last therefrom, last engaging means, with power operated mechanism organized to impart to a 125
- 130

last a diagonally downward and heelward movement to withdraw said last from its shoe.

44. A machine for removing lasts from 5 shoes having, in combination with a shoe holder, a last holder, with power operated mechanism coöperating therewith, to withdraw a last from a shoe by a generally diagonally downward last movement having a 10 substantial component of last movement heelward.

45. In a last pulling machine, means for holding a shoe for the removal of a last therefrom and power operated last removing mechanism organized to remove a last 15 from its shoe by a generally downward last movement with a lengthwise component of movement increasing as permitted by the relative positions of shoe and last.

46. A machine for removing lasts from 20 shoes having, in combination, means for holding a shoe for the removal of a last therefrom, together with power operated last removing mechanism organized to effect 25 an initial relative movement of the heel portions of the shoe and last and then to move the last lengthwise.

47. A machine for removing lasts from 30 shoes, having, in combination, a shoe holder and power operated last removing mechanism organized and arranged to effect an initial relative movement of the heel portions of a shoe and last and subsequently at a critical stage to effect a lengthwise 35 movement of the last.

48. A machine for removing lasts from 40 shoes having, in combination, means for holding a shoe for the removal of a last therefrom and power operated removing mechanism organized and arranged to effect 45 an initial relative movement of the heel portions of the shoe and last in a direction substantially perpendicular to the plane of the last bottom, and subsequently and automatically, when permitted by the relative positions of the shoe and last, to effect a lengthwise movement of the last relatively to the shoe.

49. A machine for removing lasts from 50 shoes having, in combination, means for holding a shoe for the removal of a last therefrom, and power operated last removing means operative to effect an initial relative movement of the heel portions of the 55 shoe and last in a direction substantially perpendicular to the plane of the shoe bottom and then to complete the last removing operation by withdrawing the last lengthwise from the shoe.

50. A machine for removing lasts from 60 shoes having, in combination, means for holding a shoe for the removal of a last therefrom and power operated last removing mechanism operative to effect an initial 65 relative movement of the heel portions of

the shoe and last and subsequently, and substantially as soon as the last heel has cleared the shoe counter, to complete the last removing operation by a lengthwise movement of the last.

51. A last pulling machine having, in 70 combination, shoe grippers, a last holder, and power operated mechanism for effecting relative movement of said grippers and said holder in variable directions responsive to 75 the resistance to separation offered by each individual last and shoe operated upon and including relative movement of said grippers and holder lengthwise of the shoe and last.

52. A last pulling machine having, in 80 combination, shoe grippers, a last holding spindle, and means for operating said spindle to pull a last from a shoe by movement including lengthwise last movement.

53. A last pulling machine having, in 85 combination, shoe grippers, a last holding spindle, and means for operating said spindle to effect last movement perpendicularly to the plane of the shoe bottom and lengthwise of the last and shoe.

54. A last pulling machine having, in 90 combination, shoe grippers, a last holding spindle, and means for operating said spindle to pull a last downwardly and heelward 95 out of its shoe by lengthwise movement of the last.

55. A last pulling machine having, in 100 combination, shoe grippers, a last holding spindle, a carrier for said spindle, and an operating member connected to said carrier to effect an initial movement of said spindle and a last thereon and thereafter to move said spindle to complete the removal of the last from its shoe by lengthwise movement 105 of the last.

56. A last pulling machine having, in 110 combination, a last holder, shoe holding means engaging the rear portion of a shoe, shoe sole engaging means coöperating therewith, and mechanism for relatively moving said holder and said means to separate a shoe and last.

57. A last pulling machine having, in 115 combination, last holding means, shoe counter gripping means, auxiliary shoe gripping and holding means, and mechanism for relatively moving said last holding means and said other means to separate a shoe and last.

58. A last pulling machine having, in 120 combination, a last holding spindle, shoe gripping means, auxiliary coöperating shoe gripping means, and mechanism for relatively moving said spindle and said shoe gripping means to separate a shoe and last.

59. A last pulling machine having, in 125 combination, last holding means, shoe holding means, shoe shank engaging means coöperating with the shoe holding means, and mechanism for relatively moving said last 130

holding means and said other means to separate a shoe and last.

60. A last pulling machine having, in combination, a last holding spindle, shoe grippers, shoe sole engaging means coöperating with said grippers, and operating mechanism for relatively moving said spindle and said other parts to separate a shoe and last. 5

61. A last pulling machine having, in combination, a last holding spindle, a shoe clamp, auxiliary shoe clamping and holding means, and mechanism for relatively moving said spindle and said shoe clamping means to separate a shoe and last. 10

62. A last pulling machine having, in combination, a last holder, a shoe clamp, auxiliary shoe holding means comprising shoe shank holding devices, and mechanism for relatively moving said last holder and said 15 other parts to separate a shoe and last.

63. A last pulling machine having, in combination, last holding means, shoe holding means, auxiliary shoe holding means arranged to engage a shoe sole near the line 25 between the forepart and the shank, and mechanism for relatively moving said means to separate a shoe and last.

64. A last pulling machine having, in combination, last holding means, shoe holding 30 means for engaging the rear portion of a shoe, welt crease engaging auxiliary shoe holding means, and mechanism for relatively moving said last holding means and said other means to separate a shoe and last.

65. In a last pulling machine, a last spindle arranged to oppose separation of a last therefrom, shoe grippers, welt crease engaging blades coöperating with said shoe grippers, and means for relatively moving 35 said last spindle and said other parts to separate a shoe and last.

66. A last pulling machine having, in combination, a last holder, shoe holding means having substantially right line movement 40 transversely of the shoe into work engaging position, and power driven means for effecting said movement and for thereafter relatively moving said last holder and said shoe holding means to separate a shoe and 45 last.

67. A last pulling machine having, in combination, a last holder, shoe clamping members relatively movable substantially perpendicularly to the longitudinal median line 50 of a shoe into shoe engaging position, and power driven means for relatively moving said members into work engaging position and for thereafter relatively moving said last holder and said clamping members to 55 separate a shoe and last.

68. A last pulling machine having, in combination, a last holder, shoe grippers having substantially right line movement into shoe 60 engaging position, and power driven means

operating automatically to move said shoe 65 grippers into engagement with a shoe.

69. In a last pulling machine, in combination, shoe heel clamping members, means for relatively moving said members into engagement with a shoe heel, last holding means, 70 and mechanism for effecting relative movement between said holding means and the shoe heel clamping members to separate the shoe and last.

70. A last pulling machine having, in combination, shoe clamping members arranged for substantially right line relative movement into operative engagement with a shoe, together with power driven means for moving 75 said members into shoe clamping engagement, and means operating to cause said clamping engagement to be effected under spring pressure. 80

71. In a last pulling machine, in combination, a normally open shoe clamp having 85 work engaging parts arranged to be brought into work engaging position by substantially right line movement thereof, power driven means for effecting said movement, and means for causing said movement to be yield- 90 ingly effected.

72. In a last pulling machine, in combination, shoe holding and gripping means, auxiliary shoe holding and gripping means co- 95 operating therewith, mechanism for moving said means into holding engagement with a shoe last holding means, and mechanism for relatively moving said shoe holding means and last holding means to separate a shoe and last. 100

73. In a last pulling machine, in combination, shoe counter grippers, auxiliary shoe gripping means arranged to coöperate with said counter grippers, and means for moving one of said gripping means into holding en- 105 gagement with a shoe last holding means, and mechanism for relatively moving said shoe holding means and last holding means to separate a shoe and last.

74. In a last pulling machine, in combination, shoe holding means, auxiliary shoe engaging and holding means, and mechanism for automatically moving said auxiliary means into operative engagement with a shoe last holding means, and mechanism for 110 relatively moving said shoe holding means and last holding means to separate a shoe and last. 115

75. In a last pulling machine, in combination, shoe grippers, auxiliary shoe sole en- 120 gaging and holding means, and mechanism for relatively moving said grippers and said auxiliary means into operative engagement with a shoe last holding means, and mechanism for relatively moving said shoe holding means and last holding means to separate a shoe and last. 125

76. A last pulling machine having, in com-

bination, shoe holding means arranged to form an abutment for a shoe against lengthwise movement heelward, and means for effecting relative movement of said shoe and a 5 last therein to separate said shoe and last, said movement including lengthwise heelward movement of the last.

77. In a last pulling machine, in combination, a last holder, shoe holding means for 10 engaging the rear portion of a shoe upon opposite sides thereof and arranged to form an abutment for said shoe against lengthwise movement in one direction, and mechanism for effecting movement of said last holder 15 to remove a last from said shoe, said movement including last movement in said direction.

78. In a last pulling machine, last holding means, shoe clamping members arranged to 20 prevent lengthwise movement of a shoe heelward, and means for effecting relative movement of a shoe and last to separate the shoe and last, said movement including lengthwise heelward movement of the last.

79. In a last pulling machine, in combination, shoe counter grippers formed to prevent lengthwise movement of a shoe heelward, and last removing means arranged to 25 effect last movement in directions substantially perpendicular to the plane of the shoe bottom and lengthwise heelward.

80. A last pulling machine having, in combination, shoe holding means comprising opposed independent members for engaging 30 the counter of a shoe on opposite sides thereof, a last holder, and means for relatively moving said shoe holding member and said last holder to separate a shoe and last.

81. A last pulling machine having, in combination, shoe holding means comprising opposed independent counter gripping blocks 40 of resilient material adapted to conform to the contour of a shoe counter, last holding means, and means for relatively moving said blocks and said last holding means to separate a shoe and last.

82. In a last pulling machine, in combination, shoe counter embracing means concaved both lengthwise and transversely of a 50 shoe, last holding means and means for moving said last holding means to separate a last from its shoe.

83. In a last pulling machine, in combination, a shoe counter clamp having formed 55 work engaging faces concaved both vertically and horizontally to conform substantially to the contour of a shoe counter, a last holder, and power operated mechanism for relatively moving said clamp and said last 60 holder to separate a shoe and last.

84. In a last pulling machine, last holding means, shoe counter engaging grippers concaved to conform to the vertical contour of a shoe counter, and power driven means for 65 relatively moving said last holding means

and said grippers to separate a shoe and last.

85. In a last pulling machine, in combination, means for holding a last, means for holding a shoe including means arranged to 70 engage the counter portion of the upper at opposite sides of the longitudinal median line of the shoe, said engaging means being formed and arranged to conform substantially to the vertical contour of the counter 75 portion of the shoe upper to resist movement of the heel end of the shoe in a plane substantially perpendicular to the plane of the shoe bottom, and mechanism for effecting movement of said last holding means in 80 a direction to separate a last from its shoe.

86. In a last pulling machine, in combination, means for holding a last, means for holding a shoe including means arranged to engage the counter portion of the upper 85 at opposite sides of the longitudinal median line of the shoe, and mechanism for effecting movement of said last holding means in a direction to separate a last from its shoe.

87. A last pulling machine having, in combination, last holding means, shoe holding means arranged for holding engagement with a shoe heel, and mechanism for relatively moving said last holding means and said shoe holding means to separate a shoe 90 and last.

88. In a last pulling machine, a last holder, shoe heel grippers, and means for relatively moving said last holder and said grippers.

89. In a last pulling machine, in combination, last holding means, a shoe heel clamp shaped to conform substantially to the contour of a heel from the tread face to the heel seat, and means for relatively moving said 105 last holding means and said heel clamp.

90. In a last pulling machine, in combination, last holding means, shoe heel grippers concaved to approximate the contour of the sides of a heel from the breast rearwardly, and means for relatively moving said last 110 holding means and said grippers.

91. A last pulling machine having, in combination, a last holder, means for holding a shoe, an abutment for said shoe to prevent 115 lengthwise movement heelward, and means for operating said last holder to remove a last from said shoe.

92. A last pulling machine having, in combination, a last holder, a shoe holder, a shoe 120 gage, and means for relatively moving said last holder and said shoe holder to separate a shoe and last.

93. In a last pulling machine, in combination, last holding means, shoe holding means, 125 a shoe gage for positioning a shoe with relation to said shoe holding means, and means for relatively moving said last holding means and said shoe holding means to separate a shoe and last.

94. In a last pulling machine, in combination, last holding means, shoe holding means, a shoe gage arranged to be adjustable for shoes of different lengths, and means for relatively moving said last holding means and said shoe holding means to separate a shoe and last. 70
95. A last pulling machine having, in combination, a last holder, shoe clamping members, means for effecting relative movement of said members into shoe engaging position, said means being constructed and arranged to permit the extent of said relative movement to be adjustably determined, and means for relatively moving said last holder and said shoe clamping members to separate a shoe and last. 75
96. A last pulling machine having, in combination, a last holding support, shoe clamping members, means for effecting movement of the clamping members toward each other into shoe engaging position, means for adjustably determining the extent of such movement, and means for relatively moving said last support and said shoe clamping members to separate a shoe and last. 80
97. A last pulling machine having, in combination, shoe holding means comprising opposed independent members movable to accommodate said members to the contour of a shoe from the heel breast line rearwardly, a last holder, and means for relatively moving said members and said last holder to separate a shoe and last. 85
98. A last pulling machine having, in combination, a clamp for the rear portion of a shoe, said clamp, when engaged with the shoe, being arranged automatically to accommodate itself to the contour of a shoe from the heel breast line rearwardly, last holding means, and mechanism for relatively moving said clamp and said last holding means to separate a shoe and last. 90
99. In a last pulling machine, in combination, grippers for engaging the rear portion of a shoe and pivoted to be freely self-positioning according to the contour of the shoe from the heel breast line rearwardly when brought into engagement with the shoe, a last holder, and means for relatively moving said grippers and said last holder to separate a shoe and last. 95
100. In a last pulling machine, last holding means, a shoe heel clamp arranged, when brought into engagement with the shoe heel, to be self-positioning to accommodate the clamp to the contour of a shoe heel from the breast rearwardly, and means for relatively moving said last holding means and said clamp to separate a shoe and last. 100
101. In a last pulling machine, in combination, a last holder, shoe heel grippers pivotally mounted to be freely self-positioning according to the contour of a heel from the breast rearwardly when brought into engagement with the shoe heel, and means for relatively moving said last holder and said grippers. 105
102. In a last pulling machine, last holding means, a shoe heel clamp of resilient material adapted to be self-conforming to the shape of a heel when brought into engagement with the shoe heel, and means for relatively moving said last holding means and said clamp. 75
103. In a last pulling machine, a last holder, shoe heel clamping members arranged to be pressed yieldingly against a shoe heel, and means for relatively moving said last holder and said clamping members. 80
104. In a last pulling machine, shoe sole engaging means normally inclined to position said means according to the spring of a last, a last holder, and means for relatively moving said shoe sole engaging means and said last holder in a direction to effect separation of the shoe and last. 85
105. In a last pulling machine, in combination, a last holder, shoe sole engaging means arranged to be positioned according to the shape of a last, and mechanism for relatively moving said last holder and said means in a direction to separate the shoe and last. 90
106. In a last pulling machine, a last holding device, shoe sole engaging means adjustable according to the spring of a last, and mechanism for relatively moving said device and said means to separate a shoe and last. 95
107. In a last pulling machine, in combination, last holding means, shoe holding means, auxiliary shoe engaging means arranged for tipping or swinging adjusting movement and mechanism for relatively moving said last holding means and said shoe engaging means. 100
108. In a last pulling machine, in combination, a last holder, shoe holding means, shoe shank engaging means arranged to be tipped or swung for adjustment to the spring of a last and arranged to resist accidental displacement from adjusted position, and mechanism for relatively moving said holder and said means. 110
109. In a last pulling machine, a last holder, shoe shank engaging means movable to position said means according to the height of a shoe shank, and mechanism for relatively moving said last holder and said shoe shank engaging means to separate a shoe and last. 115
110. In a last pulling machine, in combination, shoe shank engaging means movable for adjustment according to the height of a shoe shank and arranged to prevent accidental displacement from adjusted position, and mechanism for relatively moving said last holding means and said shoe shank engaging means to separate a shoe and last. 120
111. In a last pulling machine, in combination, last holding means, shoe shank engaging means arranged to be self-conforming to the shape of a shoe shank when brought into engagement with the shoe shank, and mechanism for relatively moving said last holding means and said shoe shank engaging means to separate a shoe and last. 125
112. In a last pulling machine, in combination, last holding means, shoe shank engaging means arranged to be self-conforming to the shape of a shoe shank when brought into engagement with the shoe shank, and mechanism for relatively moving said last holding means and said shoe shank engaging means to separate a shoe and last. 130

nation, shoe shank engaging means, relief springs for said shoe shank engaging means, a last holder, and mechanism for relatively moving said shoe shank engaging means and 5 said last holder to separate a shoe and last.

112. In a last pulling machine, in combination, shoe sole engaging means arranged to be spring pressed against the work, means for adjusting the spring pressure upon said 10 shoe sole engaging means, last holding means, and means for relatively moving said shoe sole engaging means and said last holding means.

113. A last pulling machine having, in combination, shoe holding means, a last holder free to assume different positions, means for maintaining said last holder in convenient angular position for the application of a last thereto, and mechanism for 20 relatively moving said shoe holding means and said last holder.

114. A last pulling machine having, in combination, shoe holding means, a last holder free to assume different positions, a 25 stop for positioning said last holder in work receiving position, and mechanism for relatively moving said shoe holding means and said last holder.

115. A last pulling machine having, in combination, shoe holding means, a last holder arranged for free manually operated swinging movement from and to work receiving position, and means for arresting the movement of the last holder into work receiving position conveniently for the application of a last to the last holder and mechanism for moving the last holder to pull the last from the shoe.

116. A last pulling machine having, in combination, shoe holding means, a last holder, a guide for the last holder, and operating mechanism for moving said last holder in a direction to separate a shoe and last.

117. A last pulling machine having, in combination, a shoe holder, a last holder 72, a carrier 70 for the last holder, guide plates b, b located on opposite sides of said carrier, and operating mechanism for relatively moving said holders to separate a shoe 50 and last.

118. A last pulling machine having, in combination, a last holder, shoe heel grippers 36, and means for relatively moving said last holder and said grippers to separate a shoe and last.

119. A last pulling machine having, in combination, a last holding spindle 72, shoe counter and heel clamps 36, 37, and means for relatively moving said spindle and said 60 clamps to separate a shoe and last.

120. A last pulling machine having, in combination, a last holder, shoe holding and gripping means, auxiliary shoe holding devices 45 for engaging the forepart of the 65 shoe, and means for effecting relative move-

ment of said last holder and said means and devices to separate a shoe and last.

121. A last pulling machine having, in combination, shoe holding means, a last spindle 72, a swinging carrier 70 for tipping said 70 spindle into holding engagement with a last, and operating mechanism for relatively moving said shoe holding means and said spindle to separate a shoe and last.

122. A last pulling machine having, in combination, shoe holding means, a last spindle 72, a swinging carrier 70 for said spindle, and mechanism for operating said spindle 72 through said carrier 70 including pivotal connections 67, 68 to said carrier substantially as described.

123. A last pulling machine having, in combination, a last holder, shoe grippers 36, carriers 35 for said grippers, operating means for the grippers comprising a cam 85 operated plunger 26 and bell cranks 30 linked to said gripper carriers and to said plunger, and means for relatively moving said last holder and said grippers to separate a shoe and last.

124. A last pulling machine having, in combination, shoe holding means, a last holder arranged for movement to pull a last from a shoe, a cam 58 substantially as described, and operating connections from 95 said cam to said last holder, whereby operative movement of said last holder is initiated at one speed and subsequently changed to a higher speed.

125. A last pulling machine having, in combination, means for holding a last, means arranged to engage the heel portion of a shoe at opposite sides of the longitudinal median line of the shoe to form an abutment for said shoe against lengthwise movement heelward, and mechanism for moving the last holding means relatively to the shoe engaging means in a direction to pull the last from the shoe.

126. A last pulling machine having, in combination, last holding means, means to engage the heel portion of a shoe at opposite sides of the longitudinal median line of the shoe, and mechanism constructed and arranged to move the last holding means relatively to the shoe engaging means and in a 110 direction both substantially perpendicular to the plane of the shoe bottom and lengthwise heelward of the shoe, to pull the last from the shoe.

127. In a last pulling machine, in combination, means to grip a shoe counter at opposite sides of the longitudinal median line of the shoe, means to engage and hold a last within the shoe, and mechanism coöperating with said last holding means arranged to effect movement of the last in a direction substantially perpendicular to the plane of the shoe bottom and lengthwise of the shoe and last completely to separate the last from the shoe.

128. In a last pulling machine, in combination, means to grip a shoe counter at opposite sides of the longitudinal median line of the shoe, means to engage and hold 5 a last within the shoe, and mechanism co-operating with said means constructed and arranged to effect relative movement between a shoe and last in a direction substantially perpendicular to the plane of the 10 shoe bottom and lengthwise of the shoe and last completely to separate the shoe and last, said mechanism including interconnected pulling parts arranged automatically to change their relative positions and 15 lines of pull with changes in the resistance to separation offered by the shoe and last operated upon.

129. In a last pulling machine, in combination, means to grip a shoe counter at opposite sides of the longitudinal median line 20 of the shoe, means to engage and hold a last within the shoe and mechanism constructed and arranged to move said last holding means completely to pull said last from said 25 shoe.

130. A last pulling machine having, in combination, shoe holding means, last holding means, with mechanism constructed and arranged to pull one of said holding means 30 relatively to the other in directions to separate a shoe and last and including interconnected pulling parts without predetermined paths of pulling movement arranged automatically to change their relative positions and the line of pulling force in 35 response to the resistance offered to separation by each shoe and last during successive stages of shoe and last separation.

131. A last pulling machine having, in combination, shoe holding means and last holding means constructed and arranged for relative movement in directions to effect separation of the shoe and last and including interconnected pulling parts without predetermined paths of pulling movement arranged 40 for relative movement to change automatically the line of pulling force in response to the resistance offered to separation 45

by each shoe and last during successive stages of separation. 50

132. A last pulling machine having, in combination, shoe holding means and last holding means with mechanism co-operating therewith and constructed and arranged to pull one of said holding means relatively to 55 the other and in a direction to separate a last and shoe, said mechanism including interconnected pulling members without predetermined paths of pulling movement constructed and arranged automatically to vary 60 their relative positions and their line of pull during successive stages of shoe and last separation in response to the resistance offered to separation by each shoe and last at different successive stages of separation. 65

133. A last pulling machine having, in combination, shoe holding means, a floating last carrier, and pulling mechanism in operative connection with said last carrier constructed and arranged to apply through said 70 carrier, two last pulling forces tending to pull said carrier and last in different directions, each of said forces acting through the carrier in proportion to the resistance offered by a shoe to last pulling movement of 75 the carrier in the direction of said force.

134. A last pulling machine having, in combination, shoe holding means, a floating last carrier, and pulling mechanism in operative connection with said last carrier constructed and arranged to apply through said carrier two last pulling forces tending to pull said carrier and last in directions longitudinally of the last and transversely of the direction of longitudinal movement, respectively, each of said forces acting through the carrier in proportion to the resistance offered by a shoe to last pulling movement of the carrier in the direction of said force. 80 85

In testimony whereof I have signed my 90 name to this specification in the presence of two subscribing witnesses.

BENJAMIN F. MAYO.
